Primary Examiner — Lauren D McVey*Assistant Examiner* — Elisa M Pujals(74) *Attorney, Agent, or Firm* — Rutan & Tucker LLP(57) **CLAIM**

The ornamental design for a plush toy, substantially as shown and described.

DESCRIPTION

FIG. 1 is a front top perspective view of a plush toy showing our new design;

FIG. 2 is a front elevation view thereof;

FIG. 3 is a rear elevation view thereof;

FIG. 4 is a left-side elevation view thereof;

FIG. 5 is a right-side elevation view thereof;

FIG. 6 is a top plan view thereof; and,

FIG. 7 is a bottom plan view thereof.

The broken lines illustrate portions of the plush toy that form no part of the claimed design.

1 Claim, 7 Drawing Sheets(56)
